UNITED STATES PATENT OFFICE.

SAMUEL SMITH, OF BROOKLYN, NEW YORK, ASSIGNOR TO MERGENTHALER LINOTYPE COMPANY, A CORPORATION OF NEW YORK.

TYPOGRAPHICAL CASTING-MACHINE.

1,255,942.

Specification of Letters Patent. Patented Feb. 12, 1918.

Application filed January 30, 1915. Serial No. 5,197.

To all whom it may concern:

Be it known that I, SAMUEL SMITH, a citizen of the United States, residing at Brooklyn, in the county of Kings and State of New York, have invented certain new and useful Improvements in Typographical Casting-Machines, of which the following is a specification, reference being had therein to the accompanying drawing.

10 My invention relates to typographical casting machines, such for instance as linotype machines of the class represented in United States Letters Patent to O. Mergenthaler, No. 436,532, wherein a bar or slug is cast in a slotted mold against a composed line of matrices, which form the type characters thereon, and thereafter is ejected from the mold and carried between a pair of trimming knives into a receiving galley, the 15 knives acting on the opposite side faces of the slug to bring it to the required thickness.

For obvious and well-known reasons, it is necessary that the slug be trimmed with great accuracy, and it is therefore important that the cutting edges of the knives be absolutely straight and parallel. This condition, however, is difficult to maintain in practice, as it is found, due to one cause or 20 another, such for instance as warping or regrinding, that the cutting edges of the knives will lose their parallelism and consequently fail to trim the slug with the proper exactitude.

25 In order to overcome these objections, I propose to divide one or both of the knives transversely into short complementary sections, and to provide means whereby they may be adjusted relatively or independently 30 to bring their cutting edges into proper alinement. The cutting edges of such short sections can be kept practically straight, as there is very little or no tendency of the sections to warp, and no substantial difficulty 35 involved in regrinding them with accuracy. As a result, when the sections are mounted in the machine, with the capability of independent adjustment, a long straight cutting edge to trim slugs of any length may 40 be readily provided. Furthermore, the sec-

tions are free to be adjusted to compensate for wear or to coöperate in such other manner as their independent adjustment will permit.

In the accompanying drawing, I have shown my invention in preferred form and by way of example, and as applied to the specific style of machine already mentioned, but obviously many changes and variations may be made therein, which will still be comprised within its spirit. Generally speaking, I desire it to be understood that I do not limit myself to any specific form or embodiment, except in so far as such limitations are specified in the claims.

65

Referring to the drawing:

Figure 1 is a horizontal section taken through a portion of a linotype machine, having my invention applied thereto;

Fig. 2 is a side view, partly broken away, 70 of one of the trimming knives as mounted in the machine; and

Fig. 3 is a detached perspective view of the knife with its sections separated.

The slug A is cast in the mold B and subsequently removed therefrom by the ejector C, which carries it between the trimming knives D and E and into the receiving galley F at the front of the machine. The knife D is fixed in position, while the knife E is carried upon an adjustable slide G, whose position is controlled and maintained by the adjusting mechanism H. All the parts so far described are or may be substantially the same as those presented in United States Letters Patent No. 1,002,281, to D. S. Kennedy.

According to my present invention, I divide the adjustable knife E into two complementary sections, E¹ and E², which are held in place upon the slide G by the clamping screws J, passing through openings J¹ in the sections. It will be noted that the openings J¹ are somewhat enlarged in order to permit the edgewise or angular adjustment of the sections. These adjustments are effected by means of set screws K, carried by the slide G, there being two such screws for each of the sections, and arranged to engage the rear edge of each section near its opposite

ends. By this construction, the knife sections may be adjusted independently of each other, either edgewise or angularly, to bring their cutting edges into exact alinement and into 5 parallelism with the edge of the companion knife D, and due to their location upon the adjustable slide G, the knife sections may be set in different positions from the knife D without disturbing their relative positions 10 on the slide. Each of the sections is also provided with a stud L which is encircled by a spring M, bearing against its head portion and the slide G respectively, and tending to urge the corresponding section 15 away from the knife D and hold it in firm contact with the set screws K. It will be understood of course that the clamping screws J are loosened previous to the adjustment of the sections and tightened thereafter.

20 While, as before stated, the independent adjustment of the knife sections is intended primarily to effect the alinement of their cutting edges and their parallelism with 25 the edge of the fixed knife D, it is to be understood that other uses may be made thereof. For instance, in some cases it would be advantageous to set one of the knife sections further from the fixed knife than its 30 complementary section, so as to trim, for example, a slug thicker at one end than at the other, or a slug having printing characters at one end of greater height than those at the other end.

35 My invention is to be distinguished from known constructions wherein one of the knives is formed with a section which can be moved from its operative position to permit the passage of an overhanging type 40 character on the slug. In these arrangements, the movable knife section has no such capability of adjustment as is present in my construction; it merely occupies two positions, one operative and the other inoperative. It was not intended to be, nor can it 45 be, set in different angular positions to insure its alinement with the main section of the knife or its parallelism with the edge of the other knife, or adjusted independently 50 so as to be set in different operative positions in relation to the fixed knife.

Having thus described my invention, its construction and mode of operation, what I claim and desire to secure by Letters Patent of the United States, is as follows:

55 1. In a typographical casting machine, the combination of a slug trimming knife divided into a plurality of complementary sections, and means whereby the said sections may be set in different operative angular positions to bring their cutting edges into proper alinement.

60 2. In a typographical casting machine,

the combination of a slug trimming knife divided into a plurality of complementary sections, a support whereon they are independently mounted, and set screws bearing 65 against the rear edges of the sections for adjusting them angularly relatively to each other to bring their cutting edges into 70 proper alinement.

3. In a typographical casting machine, the combination of two slug trimming knives, one normally fixed in position, a supporting slide carrying the other knife 75 and adjustable laterally to vary the distance between it and the fixed knife, the said adjustable knife being divided into complementary sections arranged end to end, and means whereby one of the sections of the 80 adjustable knife may be shifted laterally toward and from the fixed knife to vary the distance therebetween independently of the adjustment of the supporting slide.

4. In a typographical casting machine, 85 the combination of two slug trimming knives, one of which is divided into complementary sections, and means whereby each of said sections may be adjusted angularly independently to different operative positions to bring its cutting edge into parallelism with that of the other knife.

5. In a typographical casting machine, the combination of a slug trimming knife divided into a plurality of complementary 95 sections, and a support therefor, each of said sections being mounted on the support so as to be rocked or tilted edgewise independently of another section, for the purpose described.

100 6. In a typographical machine, the combination of a slug trimming knife divided into a plurality of complementary sections, a support whereon they are independently mounted, and a pair of set screws bearing against the rear edge of each of said sections and adapted to adjust it angularly independently of another section.

7. In a typographical casting machine, the combination of two slug trimming 110 knives, one normally fixed in position, and a supporting slide carrying the other knife and adjustable laterally to vary the distance between it and the fixed knife, the said adjustable knife being divided into a plurality 115 of complementary sections arranged end to end and each of which is supported on the slide so as to be adjustable laterally toward and from the fixed knife to vary the distance therebetween independently of the adjustment of the supporting slide.

120 8. In a typographical casting machine, the combination of a slug trimming knife divided into a plurality of complementary sections, an adjustable slide carrying the 125 knife, the said slide being provided with

set screws bearing against the rear edges of the knife sections to adjust them to different angular positions, and the said sections being secured to the slide by means of fastening screws passing through enlarged openings in the sections, all for the purpose described.

In testimony whereof, I have affixed my signature in presence of two witnesses.

SAMUEL SMITH.
